(57) **CLAIM**

The ornamental design for a code lock as shown and described.

DESCRIPTION

FIG. 1 is a perspective view of a code lock showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is a perspective view of the code lock where the code lock is in a configuration of use.

The broken lines in FIG. 9 showing numbers and symbols depict alternate in use configuration and form no part of the claimed design. The broken lines shown are included for the purpose of illustrating portions of the code lock that form no part of the claim.

1 Claim, 9 Drawing Sheets
